UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

POSITIONING DEVICE FOR CAR COUPLERS.

Application filed January 20, 1927. Serial No. 162,318.

This device relates to means for automatically positioning the coupler of a railway car by gravity. It is to be understood that the invention is not limited to the exact 5 details of construction shown and described, as it is obvious that various modifications thereof within the scope of the claims will occur to persons skilled in the art.

Two railway cars are automatically coupled together by the movement of their respective couplers forcing the tails of the pivoted knuckles behind gravity locks. The couplers are mounted in the cars so as to permit a limited amount of lateral movement. 10 Such limitation is necessary and essential because if the couplers were allowed to move too far to either side, the couplers of the two cars being coupled would pass each other and not couple, thereby defeating the object 15 of the automatic coupler. The greater the lateral movement of a coupler the less side pressure on the striking casting when the cars are going around curves. This lateral pressure forces the wheel flanges against the 20 rail causing considerable friction and wearing of the rails and wheels.

Coupler positioning devices (or centering devices as they are sometimes called) are frequently used to increase the amount of 25 permissible lateral movement of a coupler by providing automatic means for returning the couplers to the longitudinal center of the car or at least close enough thereto so that the automatic couplers will couple. This is 30 what is termed the "coupling range".

Coupler positioning devices reduce the 35 number of broken knuckles and guard arms on couplers which members are frequently bent or broken when the couplers are not 40 within coupling range. Such devices also reduce the number of accidents to trainmen as they are not required to go between the cars and position the coupler preparatory to coupling.

45 A common form of such device comprises a coupler carrier swingably suspended from any convenient part of the car (usually the striking casting) by links at each end thereof. Such a device is very dependable and 50 positive because it is actuated simply by gravity. My present invention is an improvement upon such structures and comprises means to support the carrier independently of the links, which means do not 55 interfere with the vertical removal or re-

placement of the coupler after the carrier has been temporarily removed. Such a feature is advantageous when it is desired to remove the coupler without detaching it from the draft gear, or when the rear end 60 of the coupler is enlarged to provide for a pivotal connection between the coupler and yoke (or draft gear).

Another object is to provide means to support a swingable coupler carrier in the event 65 of a failure of one or both of the supporting links, or if the end of the carrier should break off.

Another object is to provide means to retain the carrier in such a position that it 70 will support the coupler even if one (or both) of the links should fail or be lost.

In the drawings:

Fig. 1 shows a typical application of my device to a railway car.

Fig. 2 is a side elevation of Fig. 1.

Fig. 3 shows the device with one of the links missing and a broken carrier.

Fig. 4 shows a modified form.

Fig. 5 shows a detail of the carrier.

It is frequently desirable to remove or replace the coupler without detaching it from the draft gear, therefore, I provide a striking casting 2 which has the usual means 3-4 to restrict the upward and lateral movements 85 of the coupler but which is provided with an opening at its lower side for the installation or removal of the coupler 5 by raising it vertically from the ground making what is commonly called a "yoke" striking casting. 90

A great many cars are equipped with such a yoke striking casting having a swingable carry iron supported thereto by links, but if either of such links or such carrier should fail the coupler could fall upon the 95 track, and as the draft gear is attached to the car, the coupler and draft gear might form a projection which would derail the train. It has been proposed to form an integral lower portion in the striking casting 100 between the walls of which the swingable carrier moves, which portion forms an emergency coupler support and while such construction has certain advantages it does not permit of the removal or replacing of the 105 coupler without detaching it from the draft gear.

In the form shown the coupler 5 rests upon the carrier 6 and it is retained in proper position thereon by the lugs 7 which carrier 110

is swingably suspended by links 8—8 to the striking casting or any other convenient part of the car. These links are preferably formed with T-heads or trunnions 9 at each 5 end which journal in pockets in the striking casting and carrier respectively. It may be desirable to provide means, such as bolt 11, to retain the link in position. The striking casting or buffer block may be attached to the draft sill 10 or any other part 10 of the car in any convenient manner.

In my construction I provide lateral flanges 15 adjacent each end of the carrier 6 which upon the failure of the link engage 15 and are supported by lateral flanges 16 on the striking casting. The lateral flanges 15 on the carrier under normal conditions are only a slight distance above the lateral flanges 16 on the striking casting so that 20 in the event of the failure of one of the links the carrier is only lowered a very small distance which would not affect the operation of the coupler either in running service or in coupling or uncoupling. The 25 standard A. R. A. rules permit the coupler to be $1\frac{1}{2}$ " below its normal position before the car will not be accepted in interchange.

Fig. 3 shows my device wherein one of the links has been lost and one end of the 30 carrier has been broken off and the coupler moved as far as possible to one side. (Part of the striking casting is broken away.) The broken end 17 of the carrier is supported by the lateral flanges 16 on the striking casting which have been extended (18) 35 toward the center of the car to accommodate such a condition. In other words, the flanges form an emergency support for the carrier in any position it can assume in 40 service.

Fig. 4 shows a modified form wherein the striking casting is extended to form a loop 45 around each end and below the carrier 6 so that if one of the links 8 are lost or broken the lower portion of the carrier rests upon the lower portion 21 of the striking casting. This lower portion 21 of the loop

may be extended as and for the purpose of the flange (18).

The opposite walls of the striking casting 50 are positioned so that the lateral flanges of the carrier will engage them upon any lateral movement of the carrier, thereby restricting its motion longitudinally of the car.

Fig. 5 shows the carrier with its lateral 55 flanges 15 and lugs 7.

I claim:

1. In a railway car, the combination of a car part having means to restrict the upward and lateral movements of a coupler 60 and having an opening in its lower portion for the insertion of a coupler, a coupler carrier supported by swingable links to the car part, and an emergency carrier support integral with the car part. 65

2. In a railway car, the combination of a car part having means to restrict the upward and lateral movements of a coupler and having an opening in its lower portion 70 for the insertion of a coupler, and a coupler carrier having lateral flanges adjacent each end and supported by swingable links to the car part, said car part having lateral flanges engageable with the lateral flanges of the carrier to form an emergency carrier support. 75

3. In a railway car, the combination of a car part having means to restrict the upward and lateral movements of a coupler and having an opening in its lower portion 80 for the insertion of a coupler, a coupler carrier supported by swingable links to the car part, and an emergency carrier support integral with the car part comprising means to restrict the movement of the carrier longitudinally of the car. 85

4. The combination in a railway car; a car part, a car coupler, a coupler carrier supported by swingable links to said car part, and an emergency carrier support integral with the car part so positioned that when the carrier is supported by its emergency support the coupler is still supported by the said carrier. 90

ARTHUR E. SMALL.
